UNITED STATES PATENT OFFICE.

JOHN S. CARSON, OF BROOK HAVEN, MISSISSIPPI.

IMPROVED COTTON-BALE TIE.

Specification forming part of Letters Patent No. 87,541, dated March 9, 1869.

To whom it may concern:

Be it known that I, JOHN S. CARSON, of Brook Haven, Lawrence county, Mississippi, have invented a new and useful Cotton-Bale Tie; and I hereby declare the following to be a full, clear, and exact description thereof, reference being had to the accompanying drawings, making part of this specification.

My invention relates to a form of bale-tie capable of being stamped out of a plate of sheet-iron, and combining cheapness and simplicity with security, and giving great facilities in the operation of re-pressing, which is commonly done before shipment.

Figure 1 is a perspective view of my tie in its open condition; and Figs. 2 and 3 are, respectively, a perspective view and a longitudinal section of the same in its closed condition.

My tie is formed from a rectangular plate or strip of sheet metal, so cut and swaged as to afford, near one end, a series of loops, A B C D, between and around which the permanently-attached end of the hoop or band E is secured, and near the other end other loops, F G, between which the previously-bent free end of the band is inserted. All of these loops are elevated above the level of the upper and under side of the plate alternately, and the loop F has a wing, f, under which, after the

introduction of the free end of the band, the point of the hook H is passed, which hook, engaging in the bight of the band, prevents the withdrawal of the latter. To keep it always in place and facilitate insertion, I attach the shank h of said hook by a pivot, I, to the tie-plate, and prevent its accidental disengagement from the fastened band or hoop by the provision of a bulge or projection, h', which, when the band is under tension, engages within the loop F, and prevents retrograde movement of the hook.

The central portion, J, of the plate has a wing, j, projecting downward, which serves to guide the free end of the band in the act of insertion.

I claim herein as new and of my invention—

The bale-tie formed of a plate, X, of sheet-iron, having the loops A, B, C, D, F, f, and G, and latch H h h', the whole being formed and arranged substantially as set forth.

In testimony of which invention I hereunto set my hand.

JOHN S. CARSON.
